UNITED STATES PATENT OFFICE.

HERMANN POESCHE, OF CLEVELAND, OHIO.

DESIGN FOR A METAL STAND FOR ADDING-MACHINES.

SPECIFICATION forming part of Design No. 36,437, dated July 14, 1903,

Application filed June 10, 1903. Serial No. 160,897. Term of patent 7 years.

To all whom it may concern:

Be it known that I, HERMANN POESCHE, a citizen of the United States, residing at Cleveland, in the county of Cuyahoga and State of Ohio, have invented a new, original, and ornamental Design for a Metal Stand for Adding-Machines, of which the following is a specification, reference being had to the accompanying drawing, forming a part thereof.

10 The figure, as shown in the drawing, is a perspective view showing my new design.

Having thus described my invention, what I claim as new, and desire to secure by Letters Patent, is—

The ornamental design for a metal stand 15 for adding-machines, as shown.

In testimony whereof I affix my signature in presence of two witnesses.

HERMANN POESCHE.
